Attorney

UNITED STATES PATENT OFFICE.

SAMUEL L. KUNTZ, OF FORT WAYNE, INDIANA.

ANCHOR-ROPE FASTENER.

1,347,339.

Specification of Letters Patent.

Patented July 20, 1920.

Application filed April 26, 1920. Serial No. 376,453.

To all whom it may concern:

Be it known that I, SAMUEL L. KUNTZ, a citizen of the United States of America, and resident of Fort Wayne, in the county 5 of Allen and State of Indiana, have invented certain new and useful Improvements in Anchor-Rope Fasteners, of which the following is a specification.

This invention relates to improvements in 10 anchor rope fasteners for boats and the object thereof is to provide a detachable device that may be readily secured to the side of a row boat and which will serve as a shield for the edge of a boat and by means 15 of which the anchor rope may be securely fastened.

The object of the invention is accomplished by the construction illustrated in the accompanying drawings in which:

20 Figure 1 is a perspective view of the fastener mounted on the gunwale of a row-boat;

Fig. 2 is an end elevation of the fastener mounted in position, there being parts cut 25 away and in section; and

Fig. 3 is a top plan view of the fastener.

Similar characters of reference indicate corresponding parts throughout the several views and referring now to the same:

30 The base 1 of the device is comprised of a U-shaped shield having an outwardly projecting rib 2 at each of its ends, the side 3 of one of the ribs being enlarged and forming a jaw. A screw 4 extends through a

35 boss 5 in one side of the shield and has upon its inner end a clamp-plate 6. Upon the opposite side of the shield is a projecting stud 7 having mounted thereon a lever 8 which has an integral handle 9 and also

40 a curved jaw 10, the outer face 11 of the latter being rough or serrated. When the lever is in position upon the stud the roughened face of its jaw is positioned in close proximity to the inner face 12 of the jaw 3

45 on the base 1. The jaw 10 on the lever is so shaped that when its face is brought into contact with a rope 13 placed between it and the jaw 3, the rope will become clamped between the jaws 10 and 3 with more or less

50 force as the rope is drawn upwardly, so that it becomes tightly held. The curvature of the jaw 10 is also such that when it

is swung downwardly the rope becomes thereby released from being held between the jaws.

In securing the shield on the side of the boat 14 a block 15 may be inserted between the clamp-plate 6 and the side of the boat so that the clamp-plate will bear evenly in position when the screw 4 is tightened. 55 The handle 9 of the lever extends in a plane parallel with the longitudinal opening 16 through which the side of the boat extends so as not to obstruct movements of the boatman. 60

In using the device, when the anchor is thrown overboard, its rope 13 is held so as to be paid out over the top 17 of the shield and between the ribs 2 which confine it so that it does not slip off of the base onto the adjacent upper edge of the boat. When the rope is paid out to the desired extent, it is placed between the jaws 10 and 3 and clamped therebetween by moving the handle 9 downwardly. As the boat drifts and 65 the anchor rope is drawn taut it is held wedged between the jaws until released by moving the handle upwardly. By the use of the device thus constructed the upper edge of the boat is saved from being cut or 70 worn by the rope, and the rope may be quickly and effectively secured or released as occasion may arise without the necessity of forming or untying knots. 75

What I claim is:

80 In a device of the class described for a boat, a U-shaped base forming a shield for the upper edge of the boat and having a laterally projecting jaw; a securing means in connection with one side of the base for clamping the side of the boat against the 85 opposite side of the shield; and an operating lever pivotally supported in connection with one side of the shield and extending parallel therewith, and having a cam 90 shaped jaw for clamping a rope against the 95 jaw on the shield.

In testimony whereof I affix my signature in presence of two witnesses.

SAMUEL L. KUNTZ.

Witnesses:

MATILDA METTLER,
WALTER G. BURNS.
